UNITED STATES PATENT OFFICE.

DUDLEY ROBERTS, OF WALTHAM, MASSACHUSETTS.

WATCH-KEY.

SPECIFICATION forming part of Letters Patent No. 320,699, dated June 23, 1885.

Application filed July 21, 1884. (No model.)

To all whom it may concern:

Be it known that I, DUDLEY ROBERTS, of Waltham, in the county of Middlesex, of the Commonwealth of Massachusetts, have invented a new and useful Improvement in Watch-Keys; and I do hereby declare the same to be described in the following specification and represented in the accompanying drawings, of which—

10 Figure 1 is a side view, and Fig. 2 a longitudinal section, of a watch-key provided with my invention, the nature of which is defined in the claim hereinafter presented.

15 In the drawings, A denotes a watch-key, and B the handle, the upper end of the shank or stem *a* of the key being conical to extend into a correspondingly-shaped recess, *b*, in the handle. A screw, C, provided with a nicked head, *c*, extends through the handle length-20 wise of it and screws into the shank or stem of the key. The handle at its upper end is socketed or countersunk to receive the head of the screw.

25 On screwing in the screw so as to force the handle against the shank, such handle on being revolved will, by friction against the shank, revolve the key, especially when it is in engagement with the winding-arbor of a watch. If the friction is a little more than sufficient 30 to cause the key to revolve the arbor, the handle, on the arbor being wound up, will revolve on the key, without causing the latter to overstrain the mainspring or the mechanism actuated by the arbor.

35 The cone on the shank or stem and the conical recess in the handle, into which the cone extends and fits, answer two purposes—viz., to extend or increase the frictional surfaces in contact, and to pivot the handle on the stem 40 as well as on the connecting-screw. By so pivoting the handle on the stem, the liability of such handle, when revolved to loosen the

screw, is greatly lessened if not entirely avoided.

My improvement is applicable to the stem 45 of a "stem-winding watch," in which case the said stem would have to be made in two parts like the key shank or stem and handle, and they be connected by a screw arranged in them as described with respect to the said key stem and handle. The usual ratchet would be applied to the handle, and the milled head carrying the pawl to take into the said ratchet would be adapted to turn on the handle, all 50 of which will be readily understood by watch-makers.

I do not claim in a watch-key or watch the combination of the key head and barrel with a screw connecting them, and with a spring to be forced by such screw against the head or 60 barrel, in order to produce friction to hinder the turning of the head relatively to the barrel. In my watch-key I have no spring, such key being in three parts only, instead of four, as it must necessarily have when the spring 65 is employed; and, furthermore, I have no auxiliary or clamp screw to keep the screw from being revolved in the barrel.

I claim—

70 A watch-key consisting of the shank or stem *a*, having the conical end, in combination with a cylindrical handle, *B*, having the recess *b*, such recess corresponding with and receiving the conical end of the shank *a*, and the screw *c*, passing through the handle *B* into the shank 75 *a*, whereby the stem and handle are held by the contact of their conical end and recess without other instrumentality, all as fully set forth.

DUDLEY ROBERTS.
